UNITED STATES PATENT OFFICE

132,181

DESIGN FOR A STATUETTE

Leo Jiranek, New York, N. Y., assignor to Boynton and Company, Chicago, Ill., a corporation of Illinois

Application February 16, 1942, Serial No. 105,835

Term of patent 3½ years

To all whom it may concern:

Be it known that I, Leo Jiranek, a citizen of the United States and a resident of New York, in the county of New York and State of New York, have invented a new, original, and ornamental Design for a Statuette, of which the following is a specification, reference being had to the accompanying drawing, forming a part thereof, and in which:

Fig. 1 is a frontal perspective view of a statuette embodying my new design;

Fig. 2 is a perspective view of the same as seen from a right frontal direction in Fig. 1;

Fig. 3 is a perspective view of the same as seen from a left frontal direction in Fig. 1; and

Fig. 4 is a rear elevational view of the same.
I claim:

The ornamental design for a statuette, as shown and described.

LEO JIRANEK.
